17 Claims.

(Cl. 235—2)

The instant invention relates to a printing and resetting mechanism of a totalizer. It is the object of the invention to provide a simple and positive differentiation between the sub-total and total impressions and to assure the correct operation of the machine by corresponding locking mechanisms.

It is known to distinguish between the impression of a sub-total and that of an end-total by special printing designations. An arrangement is also known, in which the misuse of the sub-total impression is prevented by producing a stamping mark on the voucher upon the impression of the sub-total.

The instant invention consists in attaining the positive differentiation between the sub-total impression and the impression of the end-total by providing an arrangement whereby at the setting of the machine for an end-total, the printing voucher is moved to a different printing line from that which is used when the machine is set for the printing of an intermediate total. The invention particularly concerns a machine without an automatic zero-setting device, in which the zero-setting means for the totalizer must first be rendered free by the unlocking of a lock. In accordance with the invention, the unlocking of the lock at the same time causes a shifting of the printing voucher so that another printing line of the voucher arrives in the line of the printing type and the impression of that special type is controlled, which designates the end-total. At the same time, a locking arrangement is actuated thereby, which enforces the execution of the zero-setting of the totalizer and the resetting of the lock to its normal position before a new adding machine operation may be performed. Other inventive features are embodied in the special constructive arrangement of the invention, one embodiment of which is described hereinafter and is illustrated in the accompanying drawings, wherein,

Figure 1 is a front view of the totalizer and the locking members,

Figure 2 is a side view of Figure 1 seen from the right,

Figure 3 is a sectional view along line III—III of Figure 1,

Figure 4 shows a front elevation and Fig. 4a a plan view of the coloring band carrier of the printing device, and

Figure 5 shows, on a reduced scale, a printing voucher which is used in conjunction with the printing arrangement.

Figure 6 is a sectional view showing the reset-

ting shaft and the zeroizing pawls for the adding wheels.

In Figs. 1 and 2, a setting means in the form of a lock 2 is screwed into the side wall 1 of the machine. The lock nut 3 of the lock is connected with a disc 4 upon which is mounted a pin 5. The pin 5 extends through a recess of an arm 6 and into a curved groove 7 of a lever 8 which is pivotally mounted upon a bolt 9. At the right end of lever 8 (Fig. 3) is a series of locking teeth 10 which cooperate with a locking pawl 12, rotatably mounted upon a bolt 13, under the action of a spring 11. The locking teeth 10 operate in conjunction with the pawl 12 in the manner of a full stroke mechanism, that is, it enforces a complete rotation of the locking nut 3 for 180° when one has begun to turn this lock. Once the movement of lever 8 in either direction has caused a tilting of the pawl 12 and the engagement of the point thereof with the teeth 10, a movement of lever 8 in a reverse direction is impossible until the lever has completed its movement, after which time the pawl 12 is free to tilt in an opposite direction. This operation is occasioned by making the distance from the center of the bolt 13 to the point of the pawl 12 slightly greater than that between the arc described by the teeth 10 and the center of the bolt.

A draft rod 14 is jointedly connected with the left end of lever 8 (Fig. 3), which in turn is guided by a longitudinal slot 15 therein upon a bolt 16, and which, furthermore, carries at its upper end a pin 17. The pin 17 is embraced by a fork-shaped slot 18 on a yoke 19, and the latter is connected with the voucher frame support 21. The voucher support 21 is shiftably mounted by means of a pin 22 in a yoke 23, which is fixed upon the front wall 24 of the machine. The lower end of the voucher support 21 rests upon a yoke 25 which is likewise fixed upon the front wall 24 of the machine housing. The voucher is insertable in the support so that its lower end shown in Fig. 5 is at the top of the support.

Two swinging plates 32 are mounted upon a shaft 31 extending between the side walls of the machine, one of which plates is illustrated in Fig. 3. The totalizer shaft 33 is mounted in these swinging plates, upon which the totalizer wheels formed as type wheels 34, are rotatably mounted. Also upon the shafts 31 and 35, are mounted the tens transfer devices and the tens transfer driving mechanism. The totalizer, consisting of the adding wheels 34, may be rocked in a clockwise direction (Fig. 3), in dependency upon a setting lever, not shown, by means of the rod 36 so that

the adding wheels come into engagement with a driving gear, not shown.

Figure 4 shows the coloring band frame 41 in top and front elevation. This frame is maintained in the lower portion of the voucher support 21 by means of spring clips 42, so that the coloring band 43 lies directly in front of the type wheels 34. The coloring band 43 is fixed upon the frame 41 by means of pins or by means 10 of clamping pieces. The frame 41 also carries a projection 44 which is so shaped that it uncovers that one of the types upon a special type bearer 45 (Fig. 1), which is to designate the sub-total or end-total on the printing voucher, uncovering only one of these types and covering the other one in every position of the voucher support 21.

In order to enforce a rotation of the totalizer shaft 33 at the unlocking of the lock 2 for the 20 purpose of zeroizing the totalizer before a new adding machine operation may be performed, the following blocking mechanisms are provided:

The arm 6 (Fig. 3) has a curved groove 46 in which the pin 47 engages. The upper end of 25 the arm 6 is jointedly connected with a lever arm 48 by means of a pin member 51, and the arm 48 is pivotally mounted upon a shaft 49. The pin 51 extends to the plane of a blocking segment 52, which is pivotally mounted upon a bolt 53 30 and which is capable of rotation in a clockwise direction by the pull of spring 54. The blocking segment 52 has a recess 55 in which the pin 51 may pass, and a blocking shoulder 56 at the end of this recess, which can cooperate with the pin member 51 in the manner described hereinafter. Furthermore, the blocking segment 52 carries a 35 rectangular lug 57, which cooperates with a blocking shoulder 58 upon a holding pawl 61 rotatably mounted upon a bolt 59. The holding 40 pawl 61 is rocked in a clockwise direction by means of the pull of spring 62. The holding pawl 61 lies in the plane of a disc 63 (Fig. 1), which is connected with a sleeve 64 keyed upon the zero-setting shaft 33. The disc 63 carries 45 a lug 67 which cooperates with the left end 68 of the blocking segment 52. The three counting wheels 65 form a counter counting the adding operations exceeding the capacity of the totalizer. The counting wheels 65 of the tens and of the 50 hundreds orders are connected by means of transfer pinions 66, rotatably mounted upon a shaft 70. The tens transfer pinion 66 of the counting wheel 65 of the lowest order and of the adding wheel 34 of the highest order are connected in any way known in the art. The counting wheels are mounted upon the same shaft 33 as the adding wheels 34 and therefore, are rocked in a clockwise direction upon the swinging of the plates 32.

60 The zeroizing of the adding wheels is effected in the following manner well known in the art:

The shaft 33 is provided with a longitudinal notch 91. Each of the adding wheels 34 carries a pivoted pawl 92 which is spring pressed against the shaft 33. The end of shaft 33 is accessible 65 through an opening 33a in the wall 1 of the casing and is provided with teeth 33b to be engaged by a key for turning the shaft. When the shaft 33 is turned the notch 91 will contact with the ends of the pawls 92 and pick up the adding 70 wheels and carry them around with it through "9" to "0" so that after a complete revolution of the shaft the adding wheels will be set to zero position.

75 A disc 72 is fixed upon the main drive shaft 71

(Fig. 2), which has a recess 73. When the lock 2 for the taking of an end-total is unlocked, the nose 74 of a locking lever 75 engages in this recess 73. The locking lever 75 is pivotally mounted upon a bolt 76 and carries the pin 47 which engages in the curved groove 46 of the arm 6. In its outer position shown in dotted lines in Fig. 2 the lever 75 covers opening 33a and prevents access to the zeroizing shaft 33.

The printing platen 82 is so mounted upon the 10 front wall of the machine by means of a spring plate 81, that the platen head 83 extends through an opening 84 through the front wall, and the printing platen 82 may be pressed manually 15 against the type wheels 34. The described apparatus operates in the following manner:

The locking nut 3 of the lock 2 is unlocked by rotating it 180° in a clockwise direction, whereby the arm 6, by means of the pin 5, is moved into its downward position, shown in Fig. 3. The 20 curved groove 46 in the arm 6 causes the locking lever 75 to be rocked in a clockwise direction so that the latter uncovers opening 33a which provides 25 access to the zero-setting shaft 33, while its locking nose 74 engages in the locking disc 72 and thereby locks the main drive shaft 71, so long as the lock is maintained in its open or unlocked position. Simultaneously with the unlocking of the lock 2, the pin 5 causes the lever 8 to be rotated about its bolt 9, thereby moving 30 the voucher frame 21 into its upper position shown in Fig. 3 through the parts 15, 17 and 19. Thereby, instead of the lower printing line, as shown in Fig. 5, being in alignment with the line of type, the upper line is in front of the 35 type. The coloring band carrier 41 has also been moved so that the covering projection 44 covers the type for the sub-total and uncovers the type for the end-total upon the type carrier 45 in Fig. 1.

40 Upon the lowering of the arm 6, the pin member 51 is moved out from the recess 55 in the blocking segment 52. Since, at this time, the rectangular lug 57 does not lie in front of the shoulder 58, as explained hereinafter, the blocking segment 52 may rotate in a clockwise direction under the force of spring 54, whereby the blocking shoulder 56 comes to lie over the pin 51, thereby immediately preventing a return rotation of the lock 2 to its normal position, since 50 the arm 6 can no longer move upwardly.

By manually pressing upon the resiliently mounted printing platen 82, the impression is now taken from the type wheels 34 and 65; see the top line of Fig. 5. Thereupon, by the manipulation of a key, the zero-setting shaft 33 is rotated and thereby, the adding wheels 34 are returned to their zero-setting in the manner previously described. During this zero-setting rotation, the lug 67 of the disc 63 strikes the left end 68 of the blocking segment 52 and rocks it in a counterclockwise direction so far that the rectangular lug 57 comes to abut under the blocking shoulder 58. Since now the blocking shoulder 56 has rendered free the pin member 51, the lock 2 may be rotated back 180° to its normal position, whereby the locking nose 74 of the locking lever 75 is raised from the recess 73 of the locking disc 72, thereby freeing the main drive shaft 71. During the first following addition 70 machine operation, the totalizer is rocked about shaft 31 in a clockwise direction into engagement with the machine drive, not shown. In the course of this rocking movement, the disc 63 strikes against the left end of the holding pawl 75

61 (Fig. 3) and lifts this pawl so far that the rectangular lug 57 can slide from under the shoulder 58 so that the blocking segment 52 may execute a slight movement to the left in a clockwise direction corresponding to the difference between the diameter of the pin member 51 and the width of the recess 55. The interlock 51, 58 is therefore, eliminated after the first addition machine operation. The interlock 51, 55 on the other hand, is not affected because at this time the pin 51 finds itself in its upper position in the recess 55.

10 The intermediate or sub-total can be taken from the totalizer at any time by the depression 15 of the printing platen 82, whereby the imprint is effected in the lower printing line, shown in Fig. 5.

20 By means of the described apparatus, at the setting of the machine for the zeroizing of the 25 totalizer, the record sheet or voucher is compulsorily moved to bring opposite the type line a special area which is different from the area on which sub-totals are printed. Furthermore, a compulsory series of operations are enforced at 30 the time of a zero-setting operation and the lock must be moved back to its normal position before a new machine operation of addition may be executed.

35 Having thus described my invention, what I 40 claim is:

1. In a machine of the class described, a totalizer, printing type carried by said totalizer, a zero-setting device for said totalizer, a driving mechanism for the machine, locking means for 45 alternatively preventing operation of said zero-setting device or said driving mechanism, setting means for shifting said locking means, a support for a record sheet opposite said type, means controlled by said setting means for shifting said support relative to said type, blocking means to hold said locking means engaged with said driving mechanism, and means whereby the resetting of said totalizer releases said blocking means.

50 2. A machine as described in claim 1 wherein said locking means, said support shifting means, and one member of said blocking means are all connected to one pivoted lever operated by said setting means, and a full stroke mechanism co-operating with said lever.

55 3. The combination claimed in claim 1 wherein said blocking means comprises a pivoted blocking segment having a slot therein and a blocking shoulder at the end of said slot, a member connected with said locking means normally within said slot adapted to be withdrawn therefrom upon the withdrawal of said locking means from said zero-setting device, spring means tending to move said blocking segment to place said shoulder in front of said member, and means operated upon the resetting of said totalizer to zero for swinging said blocking segment to release said member from said shoulder.

60 4. In a machine of the class described, a totalizer, printing type positioned by said totalizer, a zero-setting device for said totalizer, a driving mechanism for the machine, locking means for alternatively preventing operation of said zero-setting device or said driving mechanism, setting means for shifting said locking means, a support for a record sheet opposite said type, means controlled by said setting means for shifting said support relative to said type, blocking means to hold said locking means engaged with said driving mechanism, means whereby said blocking means is moved to blocking position as

5 said setting means is adjusted to liberate said zero-setting device, means whereby the resetting of said totalizer renders said blocking means inoperative, and means whereby said blocking means is set to a preparatory position by the following machine operation ready to be set in effective position as said setting means is adjusted to liberate said zero-setting device.

10 5. The combination claimed in claim 4 wherein said blocking mechanism comprises a pivoted blocking segment having a slot therein and a blocking shoulder at the end of said slot, a member connected with said locking means normally within said slot adapted to be withdrawn therefrom upon the movement of said locking means 15 to engage said driving mechanism, spring means tending to swing said blocking segment, a lug on said blocking segment, and a pivoted holding pawl adjacent said blocking segment engageable with said lug to hold said blocking segment against 20 the action of said spring.

25 6. The combination claimed in claim 4 wherein said blocking mechanism comprises a pivoted blocking segment having a slot therein and a blocking shoulder at the end of said slot, a member connected with said locking means normally within said slot adapted to be withdrawn therefrom upon the movement of said locking means to engage said driving mechanism, spring means tending to swing said blocking segment, a lug on said 30 blocking segment, a pivoted holding pawl adjacent said locking segment engageable with said lug to hold said blocking segment against the action of said spring, and means movable with said totalizer during an adding operation for releasing 35 said pawl.

40 7. The combination claimed in claim 4 wherein said blocking mechanism comprises a pivoted blocking segment having a slot therein and a blocking shoulder at the end of said slot, a member connected with said locking means normally within said slot adapted to be withdrawn therefrom upon the movement of said locking means to engage said driving mechanism, spring means tending to swing said blocking segment, a lug on said blocking segment, a pivoted holding pawl adjacent said locking segment engageable with said lug to hold said blocking segment against the action of said spring, means movable with said totalizer during an adding operation for 45 releasing said pawl, said blocking segment being thereafter movable by said spring when said setting means is moved to liberate said zero-setting device, to place said blocking shoulder in front of said member, said blocking segment being movable to free said member from said shoulder when said totalizer is reset to zero.

50 8. The combination claimed in claim 4 wherein said blocking mechanism comprises a pivoted blocking segment having a slot therein and a blocking shoulder at the end of said slot, a member connected with said locking means normally within said slot adapted to be withdrawn therefrom upon the movement of said locking means to engage said driving mechanism, spring means tending to swing said blocking segment, a lug on said blocking segment, a pivoted holding pawl adjacent said locking segment engageable with said lug to hold said blocking segment against the action of said spring, means movable with said 55 totalizer during an adding operation for releasing said pawl, said blocking segment being thereafter movable by said spring when said setting means is moved to liberate said zero-setting device, to place said blocking shoulder in front of 70 75

said member, said zero-setting device having connected therewith a lug adapted to move said blocking segment as said totalizer is reset, to free said member from said shoulder.

- 5 9. In a machine of the class described, a totalizer mounted upon a rocking frame, printing type positioned by said totalizer, a zero-setting device for said totalizer, a driving mechanism for the machine, locking means for alternatively preventing operation of said zero-setting device or said driving mechanism, setting means for shifting said locking means, a support for a record sheet opposite said type, means controlled by said setting means for shifting said support relative to said type, blocking means to hold said locking means engaged with said driving mechanism, means whereby said blocking means is moved to blocking position as said setting means is adjusted to liberate said zero-setting device,
- 10 15. means whereby the resetting of said totalizer renders said blocking means inoperative, and means moved by swinging of said rocking frame to release said blocking means to a preparatory position ready to be set in effective position as said setting means is adjusted to liberate said zero-setting device.
- 20 10. In a printing mechanism for a cash register or bookkeeping machine containing a totalizer and resetting means therefor, means for controlling the resetting of said totalizer by said resetting means, printing type positioned by said totalizer, a support for a record sheet opposite said type, means governed by said controlling means for relatively shifting said support and said type to bring opposite said type for printing end totals a special area of said record sheet which is different from the area on which sub-totals are printed, means acting automatically to block said support in shifted position, and means operated by the setting of the totalizer to zero for releasing said blocking means.
- 25 30 35 40

11. In a printing mechanism for a cash register or bookkeeping machine containing a totalizer, means for resetting said totalizer, control means for preventing operation of said resetting means, printing type positioned by said totalizer, a support for a record sheet opposite said type, means governed by said control means for relatively shifting said support and said type to bring opposite said type for printing end-totals a special area of said record sheet which is different from the area on which sub-totals are printed, means acting automatically to block said support in shifted position, and means operated by the setting of the totalizer to zero for releasing said blocking means.

12. In a machine of the class described, a totalizer, means for resetting said totalizer, printing type positioned by said totalizer, a support for a record sheet opposite said type shiftable between two positions, a control means having two positions respectively for preventing operation of said resetting means and for preventing adding operations of the machine, connections whereby adjustment of said control means moves said voucher support from one of its positions to the other, means acting automatically to block said support in the position corresponding to the position of said control means preventing adding operations, and means operated by

the setting of the totalizer to zero for releasing said blocking means.

13. In a printing mechanism for a cash register or bookkeeping machine containing a totalizer, a zero-setting device for said totalizer, means for preventing operation of said device, setting means for moving said last-mentioned means to liberate said zero-setting device for a zero-setting operation, printing type positioned by said totalizer, a support for a record sheet opposite said type, means controlled by said setting means for shifting said support relative to said type to bring opposite said type for printing end-totals a special area of said record sheet which is different from the area on which sub-totals are printed, means acting automatically to block said support in shifted position, and means operated by the setting of the totalizer to zero for releasing said blocking means.

14. In a machine of the class described, a totalizer, printing type positioned by said totalizer, a support for a record sheet opposite said type shiftable between two positions, a zero-setting device for said totalizer, a cover plate for rendering said zero-setting device inaccessible, setting means for removing said cover plate, positive connections between said setting means and said voucher support whereby the latter is moved from one position to the other in accordance with the position of said setting means, means for blocking said support in the position corresponding to the removed position of said cover plate, and means operated by the setting of the totalizer to zero for releasing said blocking means.

15. In a printing mechanism for a cash register or bookkeeping machine containing a totalizer, number type positioned by said totalizer, a plurality of auxiliary type aligned with said number type, a support for a record sheet opposite said type mounted to shift, for changing the area of the record sheet upon which the type print, and means shiftable simultaneously with said support for selectively rendering ineffective said auxiliary type.

16. In a printing mechanism for a cash register or bookkeeping machine containing a totalizer, number type positioned by said totalizer, a plurality of auxiliary type aligned with said number type, a support for a record sheet opposite said type mounted to shift, for changing the area of the record sheet upon which the type print, and a cover plate mounted on said support and shaped to cover different ones of said auxiliary type in the different positions of said support.

17. In a printing mechanism for a cash register or bookkeeping machine containing a totalizer, number type positioned by said totalizer, a plurality of auxiliary type aligned with said number type, a support for a record sheet opposite said type mounted to shift, for changing the area of the record sheet upon which the type print, a coloring band, a mounting frame for said band, means for detachably connecting said frame to said support, and a cover plate on said frame shaped to cover different ones of said auxiliary type in the different positions of said support.
